Des. 226,457
Patented Mar. 6, 1973

226,457

BREAD TRAY

James D. Wilson, Orange County, Calif., assignor to
Banner Metals, Inc., Compton, Calif.

Filed July 29, 1971, Ser. No. 167,560

Term of patent 14 years

Int. Cl. D3—02

U.S. Cl. D87—1 R

Fig. 2

FIG. 1 is a top perspective view of a bread tray embodying my new design;

FIG. 2 is a side view of the bread tray;

FIG. 3 is a bottom view of the tray; and

FIG. 4 is an end view.

I claim:

The ornamental design for a bread tray, substantially as shown.
